Primary Examiner — Jennifer L Rempfer*Assistant Examiner* — Sarah A Nguyen(74) *Attorney, Agent, or Firm* — Warner Norcross + Judd LLP(57) **CLAIM**

The ornamental design for a carpet cleaner, as shown and described.

DESCRIPTION

FIG. 1 is a front perspective view of a portable carpet cleaner showing my new design;

FIG. 2 is a rear perspective view

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The details of the carpet cleaner shown in broken lines form no part of the claimed design.

1 Claim, 7 Drawing Sheets# US D1,106,630 S
